UNITED STATES PATENT OFFICE

JOHN HENRY GLENN BAYLES, OF NOTTINGHAM, ENGLAND

CIRCULAR RIB KNITTING MACHINE

Application filed March 13, 1930, Serial No. 435,550, and in Great Britain March 27, 1929.

This invention relates to circular rib knitting machines, and it refers to improvements in the means which are employed for connecting the rubber-dial in such machines, to the needle-cylinder, in order to retain the former in the correct relation to the latter.

The arrangement generally adopted is to provide the interior of the needle-cylinder with abutments, and the underside of the rubber-dial with dogs to engage with the said abutments.

As the work must pass down between these cylinder-abutments and rubber-dial dogs, on its way to the take-up roller, its passage is facilitated by employing movable rubber-dial dogs actuated by a central cam or eccentric, which is adapted to move one half of the rubber-dial dogs up to their needle-cylinder abutments, alternately with the remainder, the change taking place two or more times each revolution.

In one arrangement, the rubber-dial dogs are pivoted, and their outer ends, which engage with the needle-cylinder abutments, are moved circumferentially by a central cam.

In an earlier arrangement, a slide carried diametrically across the underside of the rubber-dial was employed, and its ends formed dogs to engage with abutments in the interior of the needle-cylinder. This slide was actuated by an eccentric arranged to give it a longitudinal movement, and thus move first one end of the slide and then the other up to a needle-cylinder abutment. Both arrangements described present considerable difficulty in making the adjustments which are necessary when a change is effected in the quality of the work produced.

It will be understood that when working up yarns made of different materials and of different thicknesses, that the fabrics produced in the machine from time to time will vary in thickness, and that it is necessary to adjust the rubber-dial dogs or the needle-cylinder abutments to compensate for the

different thicknesses of fabric, and thus maintain the correct relation between the cylinder and rubber-dial needles. In existing machines the rubber-dial dogs or the needle-cylinder abutments, are each adapted to be independently adjusted for this particular purpose, and it takes up some time. The present arrangement provides means for adjusting all the rubber-dial dogs simultaneously for the purpose described, and saves considerable time in making the necessary adjustment.

According to the present invention, independent radially or approximately radially sliding dogs, preferably four in number, are disposed on the underside of the rubber dial, these dogs are carried on a concentric member which is attached to but is angularly adjustable relatively to the dial, so that all the dogs can be angularly adjusted to the same extent at one operation. The whole of the dogs are actuated by a central cam which acts upon all the four dogs, but it must be understood that in machines of reduced diameter, the number of rubber-dial dogs employed may be reduced to three, owing to the reduced space available.

The invention is more particularly hereinafter described with reference to the accompanying drawings in which—

Fig. 1 is an elevation partly in section, and

Fig. 2 an inverted plan of my improved arrangement for connecting the rubber-dial of a rib knitting machine to the needle cylinder, the essential parts only of the machine being shown.

Like letters indicate like parts throughout the drawings.

In carrying out this invention, independent rubber-dial dogs A adapted to slide radially or approximately radially are disposed on the underside of the rubber-dial B, the number employed is preferably four as

shown in the drawings, they are carried by a concentric member F which is angularly adjustable relatively to the said dial B, and all the said dogs are actuated by means 5 of a central cam C, which rotates if the needle cylinder D is stationary, and is on the other hand stationary if the latter rotates.

The sliding dogs A described are mounted in guide-boxes E, and are formed with 10 rounded outer ends or noses A¹ to engage with the side faces of abutments D¹ fixed in the interior of the needle cylinder D. The side faces of the abutments D¹ are not disposed in radial planes, but are inclined to 15 such planes, so that the radial or approximately radial movements of the dogs A cause their noses A¹, to approach and recede from the said inclined faces of the abutments D¹. The noses of the sliding 20 dogs, and the side faces of the abutments, may however be formed, shaped and proportioned in any other approved way in carrying out this invention.

The guide-boxes E, are not directly secured to the rubber dial B, but are mounted 25 on a concentric member which as shown is a ring F located on the underside of the rubber dial B. This ring F is mounted on a seat provided for it on the underside of the 30 rubber-dial B, and is secured thereto by means hereinafter described, which permit of its being angularly adjusted to a certain limited extent relatively to the dial.

The rubber-dial dogs A are adapted to 35 slide in the guide boxes E, the latter are arranged equal distances apart on the ring F, and the central cam C is adapted to positively move the dogs A outwards, whilst their return movements are effected by means 40 of springs H, which are as shown located in recesses in the lower faces of the dogs and react upon studs J fixed in the guide-boxes E.

The guide-boxes E are secured to the ring 45 F by means of screws E¹, and the holes in the boxes through which these screws pass may be slotted, so as to permit of each guide box E being independently adjusted in the first place, after which no subsequent independent adjustment of the said boxes is necessitated by variations in the thickness of 50 the fabric produced.

In the preferred construction, the inner ends of the sliding dogs A are provided with 55 anti-friction rollers G, which are retained in contact with the central cam C by means of the springs H, previously described.

When four dogs A are provided as shown, the central cam C is adapted to move every 60 other dog up to its abutment, D¹ in the needle cylinder, alternately with the remainder, the change being effected two or more times each revolution, according to the shape of the cam C. When only three dogs 65 A are provided, they may be retracted one

at a time in regular order of succession.

The central cam C is as shown carried by a casing K which is secured on the central shaft L, whilst the rubber dial B is mounted loosely on the said shaft.

The whole of the dogs A are in the present case adjusted simultaneously, by adjusting the ring F on which they are carried, and to conveniently effect this result, the ring F is secured to the rubber dial B by 70 means of screws F¹, the holes in the ring through which these screws are carried are slotted, and the ring can be angularly adjusted to a limited extent by releasing these screws.

In order to assist this operation, a bracket 75 M which is secured to the rubber dial B, straddles the ring F and is provided with a set screw N which acts upon a stud O on the ring F. The set screw N is adapted to 80 positively move the ring in one direction, and if desired, a duplicate of the arrangement described may be provided which is adapted to move the ring F in the reverse direction.

The arrangement entirely obviates the necessity for independently adjusting each of the rubber-dial dogs, and saves considerable time whenever a change is made in the class 85 of work produced in the machine.

What I claim as my invention and desire 90 to secure by Letters Patent is:—

1. In a circular rib knitting machine, the combination of the rubber dial, a series of 100 mechanically actuated dogs which are employed for connecting the rubber-dial to the needle-cylinder, means for actuating said dogs, a member on the rubber-dial on which all the dogs are carried said member being angularly adjustable relatively to the dial 105 so that all the said dogs can be angularly adjusted to the same extent at one operation, substantially as described.

2. In a circular rib knitting machine, the combination with the rubber-dial, of an angularly adjustable member on its underside, 110 a series of dogs carried thereby which are adapted to slide radially or approximately radially, a central cam for actuating the said sliding dogs, and abutments on the 115 needle cylinder for the outer ends of the dogs to engage with, substantially as described.

3. A circular rib knitting machine according to the preceding claim 1, in which the 120 sliding dogs are carried in guide-boxes secured on the angularly adjustable member on the dial, substantially as described.

4. A circular rib knitting machine according to the preceding claim 1, in which the 125 sliding dogs are formed with rounded outer ends or noses and the faces of the cylinder abutments associated therewith are inclined to radial planes, substantially as described.

5. A circular rib knitting machine accord- 130

ing to the preceding claim 2, in which the inner ends of the sliding dogs are provided with anti-friction rollers which are held in contact with the surface of the central cam by means of springs located in recesses in the dogs, substantially as described.

5 6. A circular rib knitting machine according to the preceding claim 1, in which screws are provided for adjusting the dog carrying member angularly on the rubber-dial, substantially as described.
